Primary Examiner — Cynthia M Chin(74) *Attorney, Agent, or Firm* — Michael Best & Friedrich LLP(57) **CLAIM**

We claim the ornamental design for a carriage wheel, as shown and described.

DESCRIPTION

FIG. 1 is a perspective view of a carriage wheel embodying the invention.

FIG. 2 is a right side elevation view of a carriage wheel shown in FIG. 1.

FIG. 3 is a left side elevation view of a carriage wheel shown in FIG. 1.

FIG. 4 is a front elevation view of a carriage wheel shown in FIG. 1.

FIG. 5 is a rear elevation view of a carriage wheel shown in FIG. 1.

FIG. 6 is a top plan view of a carriage wheel shown in FIG. 1; and,

FIG. 7 is a bottom plan view of a carriage wheel shown in FIG. 1.

The broken lines are for the purpose of illustrating portions of the carriage wheel that form no part of the claim.

1 Claim, 5 Drawing Sheets(56)
